CONDIMENT DISPENSER

Leo F. Wildgen, Minneapolis, Minn., assignor to Arthur Salm Inc., Chicago, Ill., a corporation of Illinois

Filed May 23, 1963, Ser. No. 75,034

Term of patent 14 years

(Cl. D44—22)

FIG. 1 is a top plan view of a condiment dispenser showing my new design;

FIG. 2 is a front elevational view thereof;

FIG. 3 is a side elevational view thereof;

FIG. 4 is a perspective view thereof; and

FIG. 5 is a sectional view thereof taken along the line 5—5 of FIG. 2.

The dominant features of my design reside in the portions shown in full lines.

The design is characterized by a top surface which is an asymmetrical concave-convex surface, the uppermost points at opposite edges of the surface coinciding with spaced-apart horizontal planes, and the lowermost points of opposite edges of the surface defining a line which is spaced from a vertical plane parallel thereto extending through the center of area of the surface, all as shown in the drawings.

I claim:

The ornamental design for a condiment dispenser, substantially as shown and described.
